UNITED STATES PATENT OFFICE.

THEODORE C. WHEATON, OF MILLVILLE, NEW JERSEY, ASSIGNOR TO T. C. WHEATON CO., OF MILLVILLE, NEW JERSEY.

DESIGN FOR A BOTTLE.

47,393.

Specification for Design.

Patented May 25, 1915.

Application filed March 17, 1914. Serial No. 825,417. Term of patent 7 years.

To all whom it may concern:

Be it known that I, THEODORE C. WHEATON, a citizen of the United States, residing at Millville, in the county of Cumberland and State of New Jersey, have invented a new, original, and ornamental Design for Bottles, of which the following is a specification, reference being had to the accompanying drawing, forming part thereof.

The figure is a perspective view of the bottle illustrating my new design.

I claim:

The ornamental design for a bottle, as shown.

THEODORE C. WHEATON.

Witnesses:

T. C. WHEATON, Jr.,
WILLIAM A. HORTON.
